UNITED STATES PATENT OFFICE.

MARVIN R. MARSTON, OF LONG BEACH, CALIFORNIA.

AUTOMATIC TIGHTENING COT OR THE LIKE.

Application filed May 12, 1924. Serial No. 712,747.

To all whom it may concern:

Be it known that I, MARVIN R. MARSTON, a citizen of the United States, residing in Long Beach, in the county of Los Angeles 5 and State of California, have invented new and useful Improvements in Automatic Tightening Cots or the like, of which the following is a detailed specification.

This invention may be said to relate to 10 such things as cots and the like; although it will be apparent from a consideration of the following specification that the invention is not necessarily limited in its application specifically to cots but may be applied to 15 any other similar device where it is desired to tightly stretch a canvas or other flexible sheet, or where it is desired to cause any weight on the flexible sheet. It may be stated that a general object of the invention 20 is to provide a simple and effective device for the purpose of automatically stretching such a flexible sheet and maintaining it in a taut condition; or, as applied more specifically to a cot or the like, an object of 25 the invention may be stated to be to provide a device of simple and effective nature that will automatically cause the cot to be maintained tightly stretched, and a device that may be easily set up and also easily disassembled and folded into small compass. 30 Other objects and corresponding accomplishments of the invention will be understood from the following detailed specification. I also show detail improvements in 35 the mechanism of the device itself and all these things will be best understood from the following specification wherein I describe typical and preferred forms of device embodying the invention, and for this purpose I refer to the accompanying drawings 40 in which:

Fig. 1 is a perspective illustrating my improved device used as a cot;

Fig. 2 is an enlarged perspective showing 45 the details of the hinge connection between a pair of the supporting legs, and

Fig. 3 is a similar perspective showing a modified form of such hinge arrangement.

In the drawings I illustrate a device having 50 two pairs of legs 10, the legs of each pair being hinged together at their tops at 11. In a preferred structure as shown in Figs. 1 and 2, the upper ends of legs 10 slidably and removably fit into sockets 12, and the hinge halves 13 are formed integrally with these sockets, as will be fully un-

derstood from inspection of the drawings. These hinge members are also so formed and so disposed with relation to the sockets that by folding the legs upwardly they and 60 the sockets may be folded to position close together. Each leg assembly may thus be folded for transportation, or, if desired, the hinges and sockets may be folded and 65 the legs removed from them, thus making a somewhat shorter bundle. In Figs. 1 and 2 I show legs 10 as being cylindrical; but they may be of any suitable configuration. For instance, as shown in Fig. 3 at 10^a the legs may be square and fit into square 70 sockets 12^a; and the hinge 11^a may be of the structure shown in Fig. 3. In this case the hinge is so arranged with relation to the sockets that the sockets are offset from each other as appears in the drawings so 75 that the sockets and legs may be folded together.

The hinge pin 14 is provided with two hooks 15 and 16, one at each end of the pin and integral therewith. These hooks provide for the easy attachment of the two 80 brace ropes or wires 17 and the tie rope or wire 18. The braces 17 preferably are run down at an angle to the ground and may be attached to stakes or to any other convenient fastening, and are pulled up tight 85 so as to stretch the tie rope 18 between the two sets of legs. When the device is thus set up and braced, in the manner shown in Fig. 1, it is very stable and cannot be displaced or over-turned.

The cot proper is provided with the usual 90 flexible sheet 20 of canvas or any other suitable material; and the side edges of the sheet are attached to two longitudinal side 95 poles 21. This attachment may be effected in any suitable manner, for instance, the sheet may be attached to the poles by sliding the poles through hems at the edges of the sheet. The sheet and poles are put in 100 a position shown in Fig. 1 with poles on the outside of the diagonally set legs 10. The angle at which the legs are set will of course, determine the height above the ground at which the sheet will be held; and also the angle of the legs will determine the proportional amount of stretching action on 105 the sheet. For instance, if the legs are set up more acutely, the poles will have more tendency to slide down the outside surfaces 110 of the legs and therefore have more tendency to tighten the sheet. An angle some-

what as illustrated in Fig. 1 will be suitable for most purposes; and when any weight is imposed upon the sheet, that sheet, tending to force the poles down, will cause the 5 poles sliding down on the legs, to stretch the sheet transversely just in proportion to the amount of weight that is imposed upon the sheet. Thus, for a heavier weight, the sheet will be stretched more tightly. Also, 10 if the weight has any tendency to press the legs further into the ground, it will have a tendency to spread the legs further apart; thus again having a tendency to stretch the sheet. The sheet may have a flap 22 at each 15 end which may be tied up closely, as at 23, to the legs. These flaps form in effect head and foot pieces for the cot; or the one at the head may be tied so that it is somewhat elevated above the sheet to form an 20 elevated support for the sleeper's head.

Having described a preferred form of my invention, I claim:—

1. A device of the character described comprising two pairs of legs hingedly connected together at their tops and adapted to be set on a supporting surface with the legs of each pair at an angle to each other, a tie member between the pairs of legs and braces for the legs, and a cot or like member 25 comprising a flexible horizontal sheet and two longitudinal side poles attached thereto and bearing on the outer surfaces of the angularly braced legs; so that a weight on the sheet tending to move the sheet and 30 poles down tends to spread the poles 35

apart and stretch the sheet; the hinge connection between the legs of each pair comprising hinge members and a hinge pin with a hook formed at each end of the hinge pin, and the tie between the pairs of legs and 40 the braces being attached to said hooks.

2. In a device of the character described, comprising two pairs of sockets hingedly connected at their upper ends and adapted to be folded flat against each other and to 45 be extended to angular positions with relation to each other, the hinge connection embodying a hinge pin with a hook integrally formed at each end, leg members slidable into said sockets, and the pairs of assembled 50 legs and sockets being adapted to be placed upon a supporting surface spaced from each other, the legs of each pair making an acute angle with each other, a tie member extending between the two pairs and connected to 55 two of said hooks, brace members connected to the other two hooks; and a cot or like device comprising a flexible horizontal sheet and two longitudinal side poles, the side 60 poles resting on the outer surfaces of the angularly placed legs, so that a weight on the sheet tending to move the sheet and poles downwardly along the legs tends to spread the poles apart and stretch the sheet 65 transversely.

In witness that I claim the foregoing I have hereunto subscribed my name this 23rd day of April 1924.

MARVIN R. MARSTON.
